FIG. 4.

Inventor

Vincent D. Zito:

By H. L. Lutze

Atty.

UNITED STATES PATENT OFFICE.

VINCENT D. ZITO, OF HARTFORD, CONNECTICUT.

GAGE.

1,324,870.

Specification of Letters Patent. Patented Dec. 16, 1919.

Application filed May 14, 1919. Serial No. 297,043.

To all whom it may concern:

Be it known that I, VINCENT D. ZITO, a citizen of the United States, residing at Hartford, in the county of Hartford and 5 State of Connecticut, have invented certain new and useful Improvements in Gages, of which the following is a specification.

This invention relates to gages, the object 10 of the invention being the provision of an article of this character which is simple in construction and efficient in action and by which I can in a ready and simple manner, check up the accuracy of parts of various kinds and especially those of tubular construction.

The article comprises other features of 20 novelty and advantage which with the foregoing will be stated at length in the following description wherein I will set forth in detail that one of the several forms of embodiment of the invention which I have selected for illustration in the drawings accompanying and forming part of the present specification. I am not limited to this disclosure; 25 I may depart therefrom in several respects within the scope of the invention defined by the claims following said description.

Referring to said drawings:

Figure 1 is a side elevation of a gage 30 involving the invention and showing a way of using the same in connection with work.

Fig. 2 is a top plan view of said gage.

Fig. 3 is a face view of a portion of the indicating means.

Fig. 4 is a sectional detail showing a 35 piece of the work and a portion of the instrument in engaging relation therewith.

Like characters refer to like parts 40 throughout the several views which are on different scales.

The instrument may be employed with 45 advantage in many different ways. In the construction, for instance, of certain kinds of tubular work, it is desirable if not essential, for accuracy, that the interior of the work should be precisely determined. This so far as I am aware has heretofore been done by feel or really guess. I have provided an instrument by which the 50 accuracy of a tubular part interiorly may be determined with positiveness and precision, leaving therefore nothing to the imagination, and not only can I secure this result in the way noted, but I can do so in a ready

and quick manner, as I will more particularly explain hereinafter.

The device desirably includes in its make-up, two legs as 2 and 3. These might be considered the primary legs, not because they are in any sense more important than what may be considered as a secondary leg 4, but merely to better distinguish them. I will hereinafter describe a way in which the secondary leg 4 may be mounted. The primary legs are shown as having near their outer ends apertures of semi-circular form or virtually so, which mate to receive the pivot 5 headed at its opposite ends to hold it in place. It will be clear that the legs 2 and 3 can swing relatively or together about the stud or pivot 5. The legs on their outer branches near their center mount are notched to receive the free ends of the bowed spring 6, which constantly tends to spread the long branches of the legs, this action however, being resisted in some suitable way, a form of which will now be described.

The legs 2 and 3 are provided with laterally extended pins 7 and 8, with one of 80 which as the pin 7, a screw as 9 is rigid. This screw extends freely through a transverse hole in the pin 8 and its outer threaded portion receives an adjusting nut 10. If the thread of the screw 9 and the nut 10 85 be a right one, the nut 10 will be turned to the left to back it off or move it upward in Fig. 1, and on this motion, the spring 6 operating against the primary legs 2 and 3 tends to separate the forward or long 90 branches of the legs. By oppositely rotating the nut, it will act against the pin 8 and will move the long branches of the legs 2 and 3 relatively toward each other.

The primary leg 2, as will hereinafter appear, during a gaging operation, engages the work, while the primary leg 3 does not, the secondary leg 4 however, during such action engaging the work. The secondary leg is provided between its ends with an 100 outstanding ear 11, which receives a pivot 12 for instance in the form of a screw, threaded into an ear 13 extending outwardly from the clip 14, straddling and secured to the primary leg 3 adjacent the free end of the long branch thereof. The pivot 12 by which the secondary leg 4 is mounted, is 105 so disposed that the said secondary leg has

a short forward branch and a long inner branch. The forward branch of said leg 4 has a lateral extension 15 which overhangs the free end of the long branch of the primary leg 3, the outer surface of this lateral extension 15 being adapted to directly engage the interior of tubular work as 16 during the functioning of the implement, and coöoperating at such time with the free outer end of the long branch of the primary leg 2, as shown best in Fig. 1.

There is in connection with the instrument, gaging-means of suitable character, that shown and now to be described, having been found satisfactory. This gaging-means comprises what might be considered as a carrier, such as that denoted in a general way by 17. This carrier comprises a body portion 18 of practically segmental form, 20 provided at its upper end with lateral ears 19, which fit flatwise against the long branch of the primary leg and are fastened thereto in some convenient way as by screws 20. In addition to the body portion 18 is a cover 25 piece 21 fastened as by riveting or in some other suitable way, to the outwardly diverging flanges 22 of the body portion 18. The lower part of the back of the body portion 18 is furnished with a scale as 23 of practically arcuate form, the graduations reading oppositely from the central character which is assumed to be zero.

The rear end of the secondary leg 4 extends through the slot or opening 22' in 35 the left wall 22 (Fig. 3) and is reduced as at 24, to fit a perforation in the slide 25, which when in action, traverses the inner face of said left wall. Pivotaly mounted upon the front or inner face of the back of 40 the body portion 18, near the upper reduced end thereof, is a pointer, finger or needle 26, having below and comparatively close to its center of motion the pin 27, against which the longer arm of the angle or elbow lever 45 28 constantly abuts. This angle lever is shown as pivoted at its elbow to the back of the body portion 18 near the lower left side thereof and its short arm is in constant engagement with the lower end of the slide 50 or motion transferring member 25. Within the carrier 17 is a spring as 29 shown as being of coiled form, and connected at its upper or outer end with the slide 25 and at its lower end to a pin as 30 near the lower 55 end of the back of the body portion 18. Surrounding the pivot of the pointer or finger 26 is the coiled portion of a spring 31, the short branch of which acts against the pin 27 and the longer branch of which acts 60 against the right wall 22.

There are a number of ways of course in which the instrument can be used. It is customarily employed in connection with a micrometer. It will be supposed that a 65 piece of tubular work has been finished

and that its inside diameter is assumed to be a certain size. It is desired to prove this. The micrometer is initially set to this particular size and the legs 2, 3 and 4 are set within the micrometer in such way that 70 the primary leg 2 and the secondary leg 4 at their free ends will engage the micrometer in such manner that the secondary leg, through the connection described, will move the needle or pointer 26 until the free 75 end thereof comes opposite the zero mark of the scale 23. When this is done, the instrument, the subject of the present case, is introduced into the work 16, until the free ends of the legs 2 and 4 engage the wall of 80 the work at diametrically opposite points. If the work be of the exact size, the pointer 26 will be caused to come opposite the zero mark of the scale 23. If the work be under size, the free branch of the leg 4 will be 85 swung in, thereby moving the slide 25 upwardly or outwardly, the lower end of the slide as a consequence tending to move away from the short branch of the angle lever 28, and the spring 29 as a consequence being 90 stretched. As a result of this, the long arm of the angle lever 28 tends to move away from the pin 27 so that the branch of the spring 31, which is against the pin 27, can swing the pointer 26 to the right in Fig. 3 95 an amount equal to the under size, the graduations of the scale 23 being formed to represent thousandths of an inch. Should the work be over size, the spring 29 acting against the slide 25 tends to pull the same 100 downwardly or inwardly, the over size permitting this action. On such downward movement of the slide, the latter acting against the short branch of the angle lever 28, swings the longer or upper branch outwardly or to the left so that the said longer branch engaging against the pin 29 can in effect directly swing over the pointer or finger 26 to the right.

What I claim is:

1. A gage comprising two primary legs operatively associated for relative swinging movement, a secondary leg mounted for swinging movement upon one of the primary legs, to coöperate with the other primary leg during gaging, an oscillatory pointer carried by the primary leg which carries said secondary leg, spring means acting against said pointer, to move it in one direction, and spring-actuated means 115 acting against the secondary leg and also acting against the pointer in opposition to said other spring means.

2. A gage comprising two primary legs operatively associated for relative swinging movement, a secondary leg mounted upon one of the primary legs, to coöperate with the other primary leg during gaging, a fixed element attached to the primary leg 120 which carries said secondary leg, an oscil- 125

latory pointer carried by said fixed element the latter having a scale graduated oppositely from a central zero point and to be traversed by said pointer, spring means acting against said pointer to move it in one direction along the scale and spring-actuated means acting against the secondary leg to shift the same and also acting against the pointer in opposition to said other spring means.

3. A gage comprising two primary legs associated for relative swinging movement, a secondary leg mounted for swinging movement upon one of the primary legs, to cooperate with the other primary leg during 15 gaging, an oscillatory pointer carried by the primary leg which carries said secondary leg, spring means acting against the pointer to move it in one direction, a spring-actuated slide connected with the secondary leg to shift the same, and means for transmitting the sliding effect of said slide to said pointer and tending to move the same in opposition to said first mentioned spring 20 means.

4. A gage comprising two primary legs associated for relative swinging movement, a secondary leg mounted for swinging movement upon one of the primary legs, to cooperate with the other primary leg during 25 gaging, an oscillatory pointer carried by the primary leg which carries said secondary leg, spring means acting against the pointer to move it in one direction, a spring-actuated slide connected with the secondary leg to shift the same, and a lever acted upon by the slide through its spring, and operating in turn against the pointer to move the same in opposition to 30 said first mentioned spring means.

5. A gage comprising two primary legs

associated for relative swinging movement, a secondary leg mounted for swinging movement upon one of the primary legs to cooperate with the other primary leg during 45 gaging, a segmental plate fastened to the primary leg which carries the secondary leg and having side walls, a slide fitted against one of the side walls, the side wall against which the slide is fitted having a 50 slot for the passage of the inner end of the secondary leg which is connected with said slide, a pointer swinging upon said plate, the latter having a scale to be traversed by the pointer, a spring acting against the 55 pointer to move the same in one direction, a spring connected with the plate and the slide to operate the secondary leg, and a lever acted upon by the slide and operating against the pointer to shift the same in opposition to the first mentioned spring.

6. A gage comprising two primary legs operatively associated for relative swinging movement, a secondary leg pivotally mounted upon one of the primary legs, to cooperate with the other primary leg during 65 gaging, an oscillatory pointer provided with a pin adjacent its center of motion, a spring acting against said pin, a slide operable by the secondary leg, an angle lever, 70 one branch of which engages the slide and the other branch of which engages said pin, a spring acting against the slide and through the angle lever, against said pin to move the pin in opposition to the first mentioned 75 spring.

In testimony whereof I affix my signature in the presence of two witnesses.

VINCENT D. ZITO.
